UNITED STATES PATENT OFFICE.

COWLES TOLMAN, OF NEW HAVEN, CONNECTICUT, ASSIGNOR TO THE HOLCOMB CO., OF NEW HAVEN, CONNECTICUT, A CORPORATION.

WIND-SHIELD FOR VEHICLES.

953,723.

Specification of Letters Patent. Patented Apr. 5, 1910.

Application filed December 17, 1908. Serial No. 467,929.

To all whom it may concern:

Be it known that I, COWLES TOLMAN, a citizen of the United States, residing at New Haven, in the county of New Haven and State of Connecticut, have invented a new and useful Improvement in Wind-Shields for Vehicles; and I do hereby declare the following, when taken in connection with the accompanying drawings and the numerals 10 of reference marked thereon, to be a full, clear, and exact description of the same, and which said drawings constitute part of this specification, and represent, in—

Figure 1 a front or plan view partially in section of a wind shield construction in accordance with my invention. Fig. 2 a side view on a small scale of the same shown as applied to a motor vehicle. Fig. 3 an enlarged side view illustrating one of the 20 hinges. Fig. 4 a sectional view showing the upper end of the upper stump, and illustrating means of clamping the upper end of the arm to the upper sash. Fig. 5 a side view of the upper stump, detached:

This invention relates to an improvement 25 in wind shields for vehicles, and particularly to wind shields for motor vehicles, which comprise two glazed frames, the upper frame hinged to the lower frame and the upper 30 frame adapted to be turned with relation to the lower frame.

In the usual construction of wind shields, the upper frame folds forward, but cannot be held in any position except a vertical or 35 in a folded position. When a shield stands in a vertical position, wind striking it is by the movement of the vehicle drawn down onto the driver. One of the objects of this invention is to so arrange the upper portion 40 of the shield that it may be turned and locked in various positions of adjustment, whereby the currents of air are directed up, and hence over the heads of the passengers in the vehicle; and the invention consists in 45 the construction hereinafter described and particularly recited in the claims.

As common with wind shields, my improved shield consists of a lower sash 2 and an upper sash 3, the sashes having tubular 50 metal bindings 4 and 5, and the lower sash secured to the vehicle in the usual manner. The hinges at the opposite sides of the shield consist of a stump 6 which is adapted to enter the upper ends of the metal tubes 4 forming the sides of the lower sash. These sides

4 terminate at a point below the upper edge of the lower sash, and the stumps 6 are formed with shoulders 7 which rest upon the upper edges of the tubes. These stumps 6 are formed with projecting arms 8 and with hinge knuckles 9. Connected with the knuckle 9 is a knuckle 10 formed on the stump 11 which enters the tube 5 of the frame of the upper sash. This upper stump is formed with a long slot 12 and its inner 65 face with a longitudinal chamber 13.

Pivoted to the outer end of the arm 8 is a link 14 which at the outer end carries a thumb screw 15 which extends through a clearance slot 16 in the tube 5 and through 70 the slot 12 in the stump into the chamber 13, where it is provided with a nut 17 and so that by turning the screw the link 14 may be clamped to the upper frame. The length of the link 14 and the location of the slots is such 75 that when the upper sash is in the vertical position the screw will stand at the upper end of the slot and so that by turning the screw when in this position the sash will be locked vertically. By reversing the screw 80 the nut will be freed so that it can move downward in the chamber 13 and so that the upper sash may be turned to any desired angle, and when adjusted it may be held in that position by clamping the end of the 85 arm against the side of the frame. Not only may the upper sash be turned and clamped at any desired angle, but may be turned down parallel with the lower sash as shown in broken lines in Fig. 3. When turned 90 down the end of the arm will stand in the same relative position to the upper sash as when the upper sash is in the raised position and is locked in that folded position in the same way as in the open position. When the 95 upper sash is locked in the folded position it will be positively held slightly away from the lower sash so that no stops are required to prevent the two sashes from striking. Thus the upper sash may be turned up or 100 down, or to any intermediate point and be positively locked in such positions.

I claim:

1. A wind shield comprising an upper and a lower sash, hinges interposed between the sashes, said hinges comprising a lower stump formed with an outwardly projecting arm, an upper stump hinged to the lower stump, said upper stump slotted, a link pivoted to said arm and adapted to be clamped 110

to the upper stump through the edge of said upper sash, substantially as described.

2. A wind shield, comprising an upper and a lower sash having tubular metal edges, a stump mounted in the upper ends of the sides of the lower sash, said stumps each formed with rearwardly extending knuckles and a forwardly extending arm, upper stumps adapted to enter the sides of the upper sash which are formed with slots, said upper stumps formed with slots in line with the slots in the frame, said upper stumps also formed with chambers, links pivoted to

said arms and carrying clamping screws at their upper ends which extend through said slots, nuts in the chambers of the stumps with which the screws engage whereby the arms may be clamped to the upper frame, substantially as described.

In testimony whereof, I have signed this 20 specification in the presence of two subscribing witnesses.

COWLES TOLMAN.
